PETROLEUM REFINING

James L. Jezi, Swarthmore, Pa., assignor to Sun Oil Company, Philadelphia, Pa., a corporation of New Jersey

Application December 13, 1954, Serial No. 474,882

11 Claims. (Cl. 208—212)

This invention relates to petroleum refining, and more particularly to the removal of nonhydrocarbon constituents from petroleum.

An increasingly great problem in the refining of petroleum is the handling of crudes and fractions having relatively high concentrations of nonhydrocarbons such as organic nitrogen, oxygen, and sulfur compounds. In many instances, it is desirable to remove such compounds without removing substantial quantities of hydrocarbon constituents of the petroleum material. Prior to the present invention, this result has been difficult or impossible to achieve in a satisfactory manner.

According to the present invention, objectionable nonhydrocarbon constituents of petroleum are selectively removed therefrom in an economical manner which avoids various disadvantages of prior art operation. This is accomplished by contacting the petroleum charge material with an acid having ionization constant at 25° C. of at least about 1×10^{-3} , in the presence of a compound having less than five carbon atoms and selected from the group consisting of alkanols and saturated aliphatic ketones, the amount of acid on the anhydrous basis being at least 0.01 part by volume per 100 parts of charge but not greater than 4 parts per 100 parts of charge. The amount of acid on the anhydrous basis is preferably at least about 0.01 part by volume per 100 parts of alkanol, and not greater than 40 parts per 100 parts of alkanol. Preferred proportions are the following:

	Parts by volume
Petroleum charge	50 to 90
Alkanol or ketone	7.5 to 47.5
Acid	0.005 to 3.6

The treatment according to the invention may be carried out under anhydrous conditions or in the presence of small amounts of water, not exceeding 20 parts by volume per 100 parts of alkanol, and preferably not exceeding 5 parts per 100 parts of alkanol.

Suitable acids for use according to the invention include benzene sulfonic acid, bromoacetic acid, alpha-bromopropionic acid, chloroacetic acid, alpha-chloropropionic acid, fumaric acid, hydrochloric acid, oxalic acid, phosphoric acid, phosphorous acid, phthalic acid, salicylic acid, sulfuric acid, sulfurous acid, tartaric acid, thiolsulfuric acid, toluene sulfonic acid and trichloroacetic acid, etc. Some acid anhydrides can be used also, e.g. sulfur dioxide. Sulfur trioxide would be unsatisfactory in most cases, however, because of its tendency to sulfate the alkanol employed.

It has been found that the treatment according to the invention substantially improves the color and oxidation stability of the petroleum charge material treated. It is believed that this improvement results chiefly from reaction of the acid treating agent with nonhydrocarbons which are basic in reaction, and extraction of the reaction products from the charge by means of the alkanol or ketone. An important function of the alkanol or ketone is believed to be the prevention of hydrolysis of

2

the reaction products so that the latter may be effectively removed from the charge.

The alkanol or ketone employed according to the invention is one having less than five carbon atoms, and preferably less than four carbon atoms. The higher alkanols and ketones are unsuitable because of their too great solubility in oil under the conditions employed according to the invention. The suitable alkanols are methanol, ethanol, n-propanol, isopropanol, n-butanol, iso-butanol, secondary butanol, and tertiary butanol. The suitable ketones are acetone and methyl ethyl ketone. Methanol is a preferred alkanol for use according to the invention, and acetone a preferred ketone.

The process of the present invention may be applied to any suitable petroleum charge stock, e.g. crude petroleum, reduced crude, lubricating oil distillates, fuel fractions, etc. The process is particularly advantageously applied to charge stocks containing basic nitrogen compounds, though charge stocks containing other nonhydrocarbons of the types commonly occurring in petroleum are also advantageously treated according to the invention. Preferably, the charge stock is one which has not previously been acid treated or solvent refined. However, the process of the invention has been found to be particularly beneficial in further improving the color of charge stocks which have previously been treated with hydrogen for purposes of color improvement. Thus, for example, a naphthenic base lubricating oil may be hydrotreated at 450—575° F. and 10—35 atmospheres, with a space rate of 1 to 5 volumes of oil per volume of catalyst per hour, using a fixed bed of granular hydrogen treating catalyst of the type disclosed in Patent No. 2,654,696 issued October 6, 1953 to Walter N. LaPorte, and then further treated with a strong acid and an alkanol according to the invention.

In one embodiment, the present invention contemplates contacting a charge stock first with acid and alkanol or ketone as described, in order to react basic nonhydrocarbon constituents with acid, and then with a strong base and alkanol or ketone in order to react acidic nonhydrocarbon constituents with the base. The resulting alkanol or ketone solutions can be combined and further treated in an advantageous manner which is subsequently more fully described.

The invention will be further described with reference to the attached drawing, wherein Figure 1 illustrates schematically one manner in which the process of the invention can be carried out, and wherein Figure 2 illustrates schematically a further particular embodiment of the process of the invention. Referring to Figure 1, a charge oil containing small amounts of organic nonhydrocarbon materials, such as organic nitrogen, sulfur, or oxygen compounds, is introduced through line 11 into treating zone 10. A strong acid, e.g. 93% sulfuric acid, is introduced through lines 12 and 13 into treating zone 10, and an alkanol, e.g. anhydrous methanol, is introduced through lines 14 and 15 into treating zone 10, wherein the charge oil is intimately contacted with the acid and alkanol. The acid is mixed with the alkanol prior to contacting acid and oil, in order to avoid discoloring of the oil by contact with the acid. The various rates of introduction may be such as to provide, for example, 33 parts by volume of methanol per 100 parts of oil and about 0.15 part of acid per 100 parts of oil.

The oil then passes into a lower portion of treating zone 10 wherein it is washed with methanol introduced through line 15 in order to remove sulfuric acid which became incorporated in the oil during the contacting at the higher level. Treated oil containing small amounts of dissolved methanol is removed from treating zone 10 through line 16. The treated oil has been largely freed

of organic nonhydrocarbon constituents which are basic in reaction.

The treated oil may then be introduced through line 17 into treating zone 20, wherein it is contacted with methanol introduced through line 18, and with a strong base, e.g. 50° Bé. caustic soda, introduced through lines 19 and 18. The various rates of introduction may be those which are commonly used in treatments of petroleum materials with alkaline alcoholic treating agents for removal of materials acidic in reaction. The oil is washed in a lower portion of treating zone 20 with methanol introduced through line 21. Treated oil, substantially free of organic nonhydrocarbon constituents which are acidic or basic in reaction, is removed from treating zone 20 through line 22.

If desired, treated oil from zone 10 may be bypassed through line 23 around zone 20, thus eliminating for the bypassed material the treatment with alcoholic alkaline material.

Treated oil is passed through line 24 into stripping tower 25 wherein methanol is stripped from the oil and recycled through lines 26 and 27 to the various points of introduction of methanol into the treating steps. Refined oil is removed from stripping tower 25 through line 28.

The methanol phase is removed from zone 10 through line 29. This phase contains reaction products, e.g. salts of sulfuric acid with basic nonhydrocarbon constituents of the charge. Some oil, neutral organic nonhydrocarbon materials and residual sulfuric acid are generally contained in this phase.

The methanol phase is removed from zone 20 through line 30. This phase contains reaction products of sodium hydroxide with acidic nonhydrocarbon constituents of the charge, and also generally some residual sodium hydroxide.

The two methanol phases are combined and contacted with caustic soda introduced through line 31 in order to hydrolyze reaction products of nonhydrocarbons with sulfuric acid. It is to be understood that this introduction of caustic soda would be unnecessary in the case where sufficient free alkali was provided by the alkanol phase introduced through line 30.

The methanol containing basic nonhydrocarbons and reaction products of acidic nonhydrocarbons with alkali is introduced through line 32 into stripping tower 33, wherein alkanol is stripped from the nonhydrocarbon reaction products and recycled through lines 34, 35 and 27 to the various points of introduction of methanol into the treating steps. Excess water can be removed from the methanol by distillation if necessary. Make-up methanol is added to the system through line 36 as needed.

The nonhydrocarbon reaction product residue from the stripping operation is removed from tower 33 through line 37. Water is added through line 38, if necessary, in order to dissolve any salt which may be suspended in the residue. The resulting material may then be extracted with aqueous isopropanol and naphtha in order to recover alkali metal salts of acidic nonhydrocarbons in the isopropanol layer and basic nonhydrocarbons in the naphtha layer.

In the case where treating zone 20 has been bypassed, and line 30 is closed, the residue from stripping tower 33 is mainly basic nonhydrocarbon materials containing suspended salt. After addition of water, is necessary, these materials are admixed with a hydrocarbon solvent, e.g. naphtha, introduced through line 39, and then passed into separator 40, wherein an aqueous inorganic salt phase is separated and removed through line 41. The hydrocarbon phase is removed through line 42 and introduced into stripping tower 43, wherein solvent is stripped from the nonhydrocarbons and recycled through lines 44 and 39. The nonhydrocarbon residue is removed through line 45.

According to the present invention, the amount of acid

used should be not greater than 4 parts per 100 parts of oil. If greater amounts are used, the amount of salt formed upon addition of caustic through line 31 is excessive, and the stripping of alkanol in tower 33 cannot be effected without disadvantageous effects from the salt unless a rather large amount of water is added prior to the stripping operation.

Referring to Figure 2, previously untreated petroleum, such as a lubricating oil fraction which contains nonhydrocarbon constituents, is introduced into hydrogenation zone 50 through line 52, and is hydrogenated therein according to the procedure described previously. The hydrogenated oil is then introduced through line 53 into extraction zone 51, wherein it is contacted with sulfuric acid and methanol introduced through line 54. The contacting in the extraction zone is generally similar to that described previously with respect to Figure 1. A methanol solution of salts of sulfuric acid with basic constituents of the hydrogenated lubricating oil is withdrawn through line 55, and the treated petroleum is withdrawn through line 56.

The following examples illustrate the invention:

Example I

A lubricating oil distillate from reduced naphthenic base crude was treated with about 33 parts by volume of substantially anhydrous methanol per 100 parts of oil and with 1 pound of 93% sulfuric acid per barrel of oil (0.145 part by volume of H_2SO_4 per 100 parts of oil), the methanol and sulfuric acid having been previously mixed and the mixture contacted at room temperature with the oil under agitation conditions for a period of about 20 minutes. The layers were then separated and the oil washed several times with fresh alcohol in the absence of added sulfuric acid. The small amount of methanol remaining in the oil was evaporated under vacuum.

For comparison, another portion of the same distillate was treated with about 33 parts by volume of methanol per 100 parts of oil in the absence of sulfuric acid. The oxidation stabilities of the respective treated oils were determined by observing the induction period of the oils at 280° F., i.e. the time elapsing, while the oils were in contact with an oxidizing medium at that temperature, before a predetermined small amount of oxidation of the oil sample occurred. The following table shows the oxidation stability of the oil prior to treatment and after the respective treatments:

	Oxidation stability—Hrs.
50 Untreated oil	3.33
Oil treated with methanol alone	3.37
Oil treated with methanol and H_2SO_4	7.00

This example shows that the addition of only 0.145 part of H_2SO_4 to 33 parts of methanol produces a very great increase in the stabilizing capacity of the treating material.

Example II

Experiments of the same general kind as those described in Example I were performed on various charge oils using varying amounts of sulfuric acid. The following table shows the results, including those given in Example I. In each case, 33 parts of methanol per 100 parts of oil were used.

	Charge Stock	Parts H_2SO_4 Per 100 Parts Oil	Oxidation Stability		
			Untreated Oil	CH_3OH Alone	$CH_3OH-H_2SO_4$
70 A		0.145	3.33	3.37	7.00
A		0.072	3.33	3.37	6.53
A		1.45	3.38	3.37	6.72
B		0.072	3.48	4.63	4.98
C		0.145	3.10	3.28	4.78
D		0.145	3.53	4.58	6.73

This table shows that in all cases improvement in stabilizing capacity was obtained by adding small amounts of sulfuric acid to the methanol. Charge stock B was an oil obtained by a mild refining of charge stock A with hydrogen. Charge C was a transformer oil stock, and charge D was a naphthenic lubricant distillate having higher molecular weight than that of charge A.

The following table shows, for the same experiments referred to above, the color of the oil prior to treatment and after the respective treatments:

Charge Stock	Parts H ₂ SO ₄ Per 100 Parts Oil	NPA Color		
		Untreated Oil	CH ₃ OH Alone	CH ₃ OH-H ₂ SO ₄
A	0.145	3½	3	3-
A	0.072	3½	3	3-
A	1.45	3½	3	3-
B	0.072	3-	2½	3-
C	0.145	3+	2½	1½+
D	0.145	2½	2½+	2-

This table shows that in all cases improvement in color was obtained by adding small amounts of sulfuric acid to the methanol. The improvement in color was particularly notable in the case of the hydrotreated charge stock B.

The effect of treatment according to the invention on nitrogen content of a charge stock was shown in an experiment similar to the one described above on charge stock D. In this experiment, the total nitrogen content (Kjeldahl) of the charge was reduced from 0.038 percent to 0.008 percent by treatment with methanol and sulfuric acid, and the treatment reduced the basic nitrogen content, as determined by anhydrous titration with perchloric acid, from 0.024 percent to 0.001 percent.

The treatment according to the present invention is advantageous in that entirely satisfactory products can be obtained, if desired, without clay treating or the like following the treatment according to the present invention. By way of contrast, in processes where larger amounts of strong acid such as sulfuric acid are employed, clay treating or the like is generally required in order to obtain a satisfactory product. As mentioned previously, not substantially more than 4 parts by volume of acid per 100 parts of charge are employed, and preferably the amount does not substantially exceed 1 part per 100 parts of charge.

Example III

An experiment generally similar to those described in Example II was performed using acetone containing about 10 volume percent of water in place of the substantially anhydrous methanol of Example II. Improvement in color approximately as great as the corresponding improvement obtained in Example II resulted. Satisfactory separation of acetone from oil was obtained. Generally, the water content of a ketone employed, not admixed with alkanol, according to the invention will be in the approximate range from 2 to 20 volume percent, preferably 2 to 10 volume percent.

Example IV

An experiment generally similar to those described in Example II was performed using isopropanol containing about 10 volume percent of water in place of methanol. Improvement in color approximately as great as the corresponding improvement obtained in Example II resulted. Satisfactory separation of isopropanol from oil was obtained. Generally, the water content of ethanol or higher alkanol employed, not admixed with methanol will be in the approximate range from 2 to 20 volume percent, preferably 2 to 10 volume percent.

Example V

An experiment generally similar to those described in Example II was performed using a mixture of equal volumes of substantially anhydrous methanol and substantially anhydrous acetone in place of the methanol employed in Example II. The results were superior to the corresponding results obtained in Example II, in that better color and better layer separation were obtained in the case of the methanol-acetone mixture. Preferably, the amount of ketone in a ketone-alkanol mixture employed according to the invention is in the range from 25 to 90 volume percent. In the case of mixtures not containing methanol, 2 to 20 volume percent of water may be needed for satisfactory layer separation.

Example VI

An experiment generally similar to those described in Example II was performed using a mixture of equal volumes of substantially anhydrous methanol and substantially anhydrous isopropanol in place of the methanol employed in Example II. The results were superior to those obtained in Example II, in that better color and better layer separation were obtained in the case of the methanol-isopropanol mixture. Preferably, the amount of methanol in a mixture of methanol and a higher alkanol or alkanols employed according to the invention is in the range from 25 to 75 volume percent.

The process according to the invention is advantageously adapted to the preparation of charge stocks for use in catalytic cracking of petroleum hydrocarbon materials. The removal of nonhydrocarbon materials by the process according to the invention produces a superior charge stock for such catalytic cracking operations. The latter may be any of the well-known catalytic cracking processes of the prior art, e.g. those involving the use of synthetic silica-alumina cracking catalyst, activated clay catalyst, etc.

The invention claimed is:

1. Process for refining petroleum which comprises: contacting previously untreated petroleum containing basic nonhydrocarbon materials with a compound having less than 5 carbon atoms and selected from the group consisting of alkanols having the formula ROH where R is an alkyl hydrocarbon radical and saturated aliphatic ketones, in the presence of 0.01 to 40 volume percent, based on said compound, of an acid having ionization constant at 25° C. of at least about 1×10^{-3} , said petroleum being in contact with said compound during the entire period of contacting of said petroleum with said acid, the amount of acid on the anhydrous basis being at least about 0.01 part by volume per 100 parts of petroleum but not greater than about 4 parts per 100 parts of petroleum, and the amount of water present being not greater than about 20 parts per 100 parts of said compound; and separating petroleum in liquid phase from said compound in liquid phase.
2. Process for refining petroleum which comprises: contacting previously untreated petroleum containing basic nonhydrocarbon materials with methanol in the presence of 0.01 to 40 volume percent, based on methanol, of sulfuric acid, the amount of acid on the anhydrous basis being at least about 0.01 part by volume per 100 parts of petroleum but not greater than about 4 parts per 100 parts of petroleum, and the amount of water present being not greater than about 20 parts per 100 parts of alkanol; said petroleum being in contact with said methanol during the entire period of contacting of said petroleum with said acid separating the petroleum from the methanol; contacting the separated petroleum with methanol in the presence of caustic soda, thereby to react caustic soda with acidic constituents of the petroleum; separating the petroleum from the methanol; combining the methanol portions separated respectively in the two separating steps recited; and recovering non-

hydrocarbon constituents of the combined methanol portions.

3. Process according to claim 1 wherein petroleum is contacted with a mixture of an alkanol as defined and a ketone as defined.

4. Process according to claim 1 wherein petroleum is contacted with a mixture of methanol and a higher alkanol.

5. Process according to claim 1 wherein said compound is methanol.

6. Process according to claim 1 wherein said acid is sulfuric acid.

7. Process according to claim 1 wherein said acid is hydrochloric acid.

8. Process according to claim 1 wherein petroleum is subsequently separated from a mixture of said compound and salts of said acid with basic nonhydrocarbon constituents of the petroleum, a strong base is added to said mixture thereby to form salts of said acid and said base and liberate said basic nonhydrocarbon constituents, said compound is distilled from the resulting mixture, and basic nonhydrocarbon constituents in the distillation residue are separated from said salts.

9. Process according to claim 2 wherein methanol is distilled from the combined methanol portions, water is added to the distillation residue to dissolve sodium sulfate, and sodium salts of said acidic constituents of the petroleum are separated from basic nonhydrocarbon constituents of the petroleum.

10. Process according to claim 1 wherein the amount of said compound is at least 7.5 parts per volume per 90 parts of said petroleum.

11. Process for refining petroleum which comprises: hydrogenating previously untreated petroleum at a temperature within the approximate range from 450° F. to

575° F. and a pressure within the approximate range from 10 to 35 atmospheres in the presence of a granular hydrogen treating catalyst; and contacting the resulting petroleum containing basic nonhydrocarbon materials with a compound having less than 5 carbon atoms and selected from the group consisting of alkanols having the formula ROH where R is an alkyl hydrocarbon radical and saturated aliphatic ketones, in the presence of 0.01 to 40 volume percent, based on said compound, of an acid having ionization constant at 25° C. of at least about 1×10^{-3} , said petroleum being in contact with said compound during the entire period of contacting of said petroleum with said acid, the amount of acid on the anhydrous basis being at least about 0.01 part by volume per 100 parts of petroleum but not greater than about 4 parts per 100 parts of petroleum, and the amount of water present being not greater than about 20 parts per 100 parts of said compound; and separating petroleum in liquid phase from said compound in liquid phase.
